UNITED STATES PATENT OFFICE.

ALBERT L. LORD AND BLUFORD W. BROCKETT, OF CLEVELAND, OHIO, ASSIGNEES TO THE GUGGENHEIM LAUNDRY MACHINERY COMPANY, OF CLEVELAND, OHIO, A CORPORATION OF OHIO.

IRONING-PRESS.

1,130,415.

Specification of Letters Patent.

Patented Mar. 2, 1915.

Application filed April 22, 1912. Serial No. 692,236.

To all whom it may concern:

Be it known that we, ALBERT L. LORD and BLUFORD W. BROCKETT, citizens of the United States, residing at Cleveland, in the county of Cuyahoga and State of Ohio, have invented certain new and useful Improvements in Ironing-Presses, of which the following is a specification.

This invention relates to improvements in laundry machinery and particularly to ironing presses for ironing the bosoms of shirts and waists.

More specifically the invention relates to a machine comprising a movable ironing member or chest having a cut out portion 15 for receiving the neck band, together with an ironing board and neck band former arranged so that the forward curved portion which engages within the neck band at the front is fixed with respect to the corresponding curve of the movable ironing chest while the ironing board itself and the remaining portion of the neck band forming mechanism, together with the yoke ironing 20 mechanism, is adjustable to any size of shirt or waist to be operated upon.

The invention may be further briefly summarized as consisting in the construction and combination of parts hereinafter set 30 forth in the following description, drawings and claims.

Referring to the drawings, Figure 1 is a side elevation of the machine; Fig. 2 is a front elevation; Fig. 3 is a vertical section 35 of a portion of the machine showing parts in elevation for clearness; Fig. 4 is a top plan view of the ironing board and neck band forming mechanism; Fig. 5 is a section upon the line 5—5 of Fig. 3; Fig. 6 is an 40 enlarged detail view of the neck band forming mechanism and associated parts; Fig. 7 is a sectional view of the same; Fig. 8 is a detail view of the treadle mechanism; Fig. 9 is a detailed view of the connection between the rod 40 and the rod 42, and Fig. 45 10 is a rear elevation of a portion of the yoke ironing plate.

In carrying out the invention any preferred form and construction of parts may 50 be employed so long as they possess the necessary characteristics, but I have shown one form in the drawings which is highly effective in operation, and in such embodiment 55 1 represents the main frame which is of any preferred construction so long as it

meets with the requirements of the machine. This frame is provided with suitable bearings 2 for receiving a main shaft 3 supporting a main driving gear 4 driven in any suitable manner, this mechanism does not 60 form any part of the present invention. The frame is still further provided with a fixed bed 5, as shown clearly in Figs. 2, 3 and 5, provided with rollers 6, as shown, engaging in suitable grooves 7 in the underside of the ironing board 8 which is of hollow construction to provide for a steam space 9. This ironing board is provided with a slot or recess 9^a at its forward end extending through the ironing board for a 65 purpose to be described. It is also provided with a longitudinal recess 10 for a purpose to be further described. This ironing board 8 is also still further provided with a yoke ironing member 11 having a yoke ironing 70 plate 12 pivoted thereto in any suitable manner and extending up in the back to the height of the neck band former to be described as shown in Fig. 10. Slidably mounted in the recess 10 is a bar 13, shown 75 in Figs. 3, 4 and 5, and this bar is protected upon its upper surface by means of a plate 14 secured to the ironing board and extending from the front edge to a point near the back end of the board. At the rear 80 end of the ironing board the bar 13 is provided with an upward extension 15 to which is secured the forward curved portion 16 of the neck band former, this mechanism being clearly shown in Figs. 6 and 7. The 85 arrangement of the bar 13 and the projection 15 is such that the board with the plate 14 may move longitudinally through the various adjustments without touching the projection 15. The forward member 16 of the 90 neck band former is provided with two diagonally disposed slots 18, each of which receives a sliding member 19 having at the end thereof a foot portion 20 having a curved edge face for fitting into the back outer 95 corners of the neck band. The forward portion 16 is provided with suitable recesses 21 at each back corner for receiving the corresponding foot portion 20. A plate 16' covers the forward portion 16 and the foot 100 portions 20 and when the foot portions 20 are drawn inward into the recesses 21 the entire edge of the former conforms to the configuration of the plate. Each of the 105 slides 19 is provided with a downwardly ex- 110

tending pin 22 having thereon a friction roller 23 which engages in a slot 24 provided in a projection 25 carried rigidly by the ironing board. The arrangement of these parts is such that upon the movement of the ironing board with respect to the forward curved portion of the neck band former the foot portions 20 of the neck band former are moved backward and outward so as to expand within the neck band. The bar 13 is secured at its forward end, as shown in Fig. 3, to a bracket 26 passing up through the recess 9. This bracket is rigidly secured at its lower end to the frame 1 and is provided with a threaded boss 27 for receiving a screw 28 provided with a hand wheel 29 at one end and a ball 30 at the opposite end mounted in a suitable socket formed by the members 31 and 32, shown in Fig. 5, secured to a downwardly extending member 33 either secured to or forming a part of the ironing board. This member projects through a suitable opening in the bed 5 and is bifurcated at its lower end to form ears 34 and 35 for a purpose to be described.

It will be seen from the foregoing that by the manipulation of the hand wheel 29 and consequently the screws 28, the ironing board 8 may be shifted longitudinally upon the bed 5, and this movement does not affect the forward curved portion of the neck band former, or in other words, the ironing board and the foot portions 20 of the neck band former are moved back and forth so as to expand the neck band properly and release the same while the forward portion of the neck band former remains stationary and fixed.

Mounted in the frame is a suitable yoke ironer bed frame 36 provided with suitable recesses 37 receiving rollers 38 mounted under a yoke presser 39 of any preferred form and arranged to coöperate with the yoke ironer portion of the ironing board and with the yoke ironing plate 12. Connected to this yoke presser in any suitable manner is a rod 40 which extends forward and is provided with a curved portion 41 and is pivoted at its end by means of a pin 40' to a rod 42 connected to a treadle 43 pivoted in the base and also pivoted to links 44 mounted upon a pin 45 extending through the ears 34 and 35, as shown in Fig. 5. The treadle 43 is mounted in suitable ears 46 forming a part of the base and is provided with a lug 47 adapted to be engaged by the end of a releasing treadle 48 mounted in ears 49 secured to the base. A spring 50 is secured to the rod 42 and to the frame to pull the rod to the right as shown in Fig. 3. The yoke presser and treadle mechanism are arranged so that when the treadle 43 is depressed the links 44 are rocked about the pin 45 in a counter-clockwise direction, and

the yoke presser is pulled up tightly into pressing or ironing position, when the curved portion 41 of the rod 40 passes down over the pin 45 so as to carry the pivotal point between the rod 40 and the rod 42 below the pivot 45 thereby causing the yoke presser to remain in pressing position until released. To release the yoke presser the treadle 48 is depressed, thereby raising the treadle 43 and causing the rod 40 to be thrown up above the pin 45, the spring 50 pulling the rod 42 to the right and causing the yoke presser to move back. This treadle mechanism does not interfere in any way with the adjustment of the ironing board as and the neck band former, by reason of the fact that the mechanism for pulling the yoke presser into operative position is connected to a downwardly projecting member which forms a part of the ironing board 8 and since the rod 42 is pivoted to the treadle 48 this mechanism is free to move back or forward with the ironing board.

Secured to the frame is a pair of supporting brackets 51 extending forward and each is provided with a socket 52. These sockets receive the trunnions 53 of a movable ironing chest 54 provided with a curved cut out portion 55 at the back to conform to the configuration of the forward portion of the neck band former, and this portion of the movable chest is so arranged that a space is left between the face of this portion and the forward portion of the neck band former to allow for the neck band itself. This place is clearly shown in Fig. 3. This movable ironing chest is swung by any suitable mechanism but the mechanism shown comprises a pair of beams 56 pivoted to the base and connected intermediate their ends to links 57 pivoted to a crank pin 58 secured in the main driving gear 4. The upper ends of those beams are connected by a shaft 59, and this shaft carries a member 60, which receives a rod 61 connected to a member 62 swiveled to ears 63 forming a part of the movable ironing chest. A spring 64 is arranged between the member 60 and the member 62. The beams 56 and the connection between them and the movable ironing chest form a toggle arrangement whereby when the toggle is straightened the member 60 exerts a great pressure upon the spring and thereby forces the movable ironing member downward on the work. It is quite obvious that when the beams are pulled backward that the movable ironing chest will be elevated. A suitable ironing padding 65 is arranged upon the ironing board, and this padding extends back on either side of the member 15 which forms a part of the bar 13, as shown clearly in Figs. 6 and 7.

In using the machine, the operator collapses the neck band former and then places

the neck band of the shirt around the former with the shirt arranged over the ironing board and with the back of the shirt pulled down over the yoke ironing member and yoke ironing plate 12. The hand wheel 29 is then rotated in the proper direction to cause the ironing board with the rear foot portions 20 of the neck band former to move backward until the neck band is stretched, it being understood that the neck band has 10 been ironed previously on a neck band ironing machine or in some other manner. The shirt is then pulled down and tightened over the ironing board in any suitable manner. The treadle 43 is then depressed causing the yoke presser to be moved into place. Power is then transmitted to the gear 4 and the movable ironing chest is lowered upon the work when the ironing operation is 20 started and upon its completion the machine is opened up and the shirt is removed.

Having described our invention, we claim:—

1. In an ironing press, an ironing board, 25 a neck band former comprising a portion fixed relative to the ironing board and a movable portion, means for simultaneously moving the ironing board and the movable portion of the neck band former to adjust 30 the latter to various sizes of neck bands, an ironing chest coöperating with the ironing board, and means for bringing about a relative movement of the ironing board and chest.

2. In an ironing press, an ironing chest 35 having a recess for the neck band former, an ironing board, a neck band former comprising a portion fixed against movement with the ironing board and other portions movable with the ironing board, means for moving the board and the movable portions of the neck band former to adjust the neck band former to various sizes of neck bands, and means for bringing about a relative movement of the ironing chest and the ironing board.

3. In an ironing press, an ironing chest 50 having a recess for the neck band former, an ironing board, a neck band former comprising a forward curved portion fixed against movement with the ironing board and having a fixed relation with respect to the neck band recess of the chest and also having foot portions movable with the ironing board, means for moving the ironing board and the foot portions of the neck band former to adjust the latter to various sizes of neck bands, and means for bringing about a relative movement of the ironing chest and ironing board.

4. In an ironing press, a movable ironing member having a neck band recess, an ironing board, yoke ironing mechanism coöperating with the ironing board, a neck band former mounted upon the ironing board and

having a portion fixed with respect to the board and a movable portion, means for shifting the board, the yoke ironing mechanism and the movable portion of the neck band former to adjust the neck band former to various sizes of neck bands, and means for bringing about a relative movement of the ironing member and the ironing board.

5. In an ironing press, an ironing chest 70 having a neck band recess, a movable ironing board, a yoke ironing member carried thereby, a yoke presser coöperating with the yoke ironing member, a neck band former mounted upon the board and having a portion fixed against movement with the ironing board, and a movable portion, means for simultaneously shifting the ironing board and the movable portion of the neck band former to adjust the latter to various sizes of neck bands, and means for bringing about 75 an engagement of the ironing chest with the ironing board.

6. In an ironing press, a frame, an ironing member or chest having a neck band recess, 90 an ironing board, a neck band former comprising a front portion and back portions, said portions being relatively movable, means connecting the front portion directly to a fixed part, connections between the movable portions and the ironing board, 95 means for moving the ironing board, thereby adjusting the neck band former to the neck band of the shirt operated upon and means for bringing about a relative movement between the ironing chest and ironing 100 board.

7. In an ironing press, a frame, an ironing member or chest, an ironing board slidably mounted upon the frame and having a longitudinal recess in its upper face, a member 105 arranged in the recess in said ironing board and having one end secured to the frame, a neck band former comprising a forward curved portion mounted upon the member arranged in the recess of said ironing board, 110 and having a fixed relation with respect to the curved recess of the ironing member or chest, and movable portions of the neck band former, connections between the movable portions and the ironing board, suitable 115 means for sliding the ironing board and thereby adjusting the neck band former, and means for bringing about a relative movement between the ironing chest and ironing board.

8. In an ironing press, a frame, an ironing member or chest, an ironing board slidably mounted on the frame and having a longitudinal recess in its upper surface, a bar slidably mounted in said recess and having one 125 end secured to the frame, a neck band former comprising a forward curved portion and rear movable portions, means for securing the forward curved portion to the end of said bar, mechanism mounted be- 130

tween a fixed part and the slidable ironing board for adjusting the ironing board and the movable portions of the neck band former, and means for bringing about a relative movement between the ironing chest and ironing board.

9. In an ironing press, a frame, an ironing member or chest, an ironing board, a neck band former, a yoke presser supported upon the frame, suitable mechanism between the yoke presser and the ironing board for drawing the former toward the latter, mechanism between the frame and said ironing board for adjusting the position of the board and the neck band former to the work, and means for bringing about a relative movement between the ironing chest and ironing board.

10. In an ironing press, a frame, a movable ironing member or chest, an ironing board movably mounted on the frame, a yoke presser movably mounted on the frame, toggle mechanism between the movable ironing board and the yoke presser adapted when the toggle is straightened in one position to draw the yoke presser into engagement with the ironing board, means for operating this mechanism, a neck band former, and means for bringing about a relative movement between the ironing chest and ironing board.

11. In an ironing press, a frame, a movable ironing member or chest, an ironing board movably mounted on the frame, a yoke presser movably mounted on the frame, toggle mechanism between the movable ironing board and the yoke presser adapted when the toggle is straightened in one position to draw the yoke presser into engagement with the ironing board, means for operating this mechanism, a neck band former, means for adjusting the neck band former, and means for bringing about a relative movement between the ironing chest and ironing board.

12. In an ironing press, a frame, a movable ironing member or chest having a neck band recess, an ironing board slidably mounted on the frame and having a recess in its upper surface, a bar slidably mounted in said recess, a guard plate secured to the ironing board above said bar, means for securing one end of the bar to a stationary part, and a neck band former comprising a forward portion mounted on said bar near one end of the ironing board and having guiding recesses therein, slides mounted in said recess, rear neck band engaging portions mounted on said slides, projections carried by said slides, and means carried by the ironing board for engaging the projections carried by said slides and adjusting the neck band former with the movement of the ironing board, means for moving the ironing board, and means for bringing about

a relative movement between the ironing chest and ironing board.

13. In an ironing press, a frame, an ironing chest, an ironing board slidably mounted on the frame and having near one end thereof transverse guiding portions, a neck band former comprising a forward portion fixed with respect to the ironing board, and rear foot portions movable with respect to the forward portion of the neck band former, means carried by the movable foot portions and engaging in the transverse guiding portions of the ironing board whereby upon the movement of the ironing board there will be a movement of the foot portions, means for moving the ironing board, and means for bringing about an engagement of the ironing chest and ironing board.

14. In an ironing press, a frame, an ironing chest, an ironing board slidably mounted on the frame and having near one end thereof transverse guiding portions, a neck band former comprising a forward portion fixed with respect to the ironing board, and rear foot portions movable with respect to the forward portion of the neck band former, a projection carried by each foot portion for engagement with the transverse guiding portion of the ironing board whereby upon the movement of the ironing board there will be a movement of the foot portions, means for moving the ironing board, and means for bringing about an engagement of the ironing chest and ironing board.

15. The combination with a support, of a movable bosom board for supporting a neck band, a stationary neck band engaging member mounted on the support, and neck band engaging devices connected with the movable bosom board.

16. The combination with a support, of a bosom board slidably arranged on the support, said board having an opening therein, a neck band engaging member secured to the support by means of a connection projecting through the opening, and neck band engaging devices having connection with the board and adapted to move therewith.

17. The combination with a support of a bosom board slidably arranged on the support, said board having an opening therein, a neck band engaging member secured to the support by means of a connection projecting through the opening, neck band engaging devices slidably mounted on the engaging member, and an actuating device mounted on the board and having connection with the neck band engaging devices.

18. The combination with a support, of a bosom board slidably arranged on the support and having an opening therein, a neck band engaging member secured to the support by means of a connection projecting through the opening, guide ways on the neck band engaging member, neck band engaging

devices slideable in said guideways and having projections thereon, and an actuating device mounted on the board and provided with slots in engagement with the aforementioned projections.

19. In an ironing press, a chest, a bosom board, a neck band former comprising a forward portion and foot portions relatively adjustable, padding arranged upon the board and extending under the edges of the foot portions throughout the various adjustments of the neck band former.

20. In an ironing press, a chest, a bosom board, an adjustable neck band former, a

padding arranged upon said board extending under the forward portion and under the foot portions throughout the various adjustments of the neck band former, and a support for the neck band former extending through said padding.

In testimony whereof we affix our signatures in presence of two witnesses as follows.
